UNITED STATES PATENT OFFICE

JULIUS A. SAND, JR., OF DETROIT, MICHIGAN

DESIGN FOR A HOUSING FOR A LIQUID-CONTAINER VENDING MACHINE

Application filed December 10, 1930. Serial No. 37,935. Term of patent 3½ years.

To all whom it may concern:

Be it known that I, JULIUS A. SAND, Jr., a citizen of the United States, residing at Detroit, in the county of Wayne and State of Michigan, have invented a new, original, and ornamental Design for a Housing for a Liquid-Container Vending Machine, illustrative of the accompanying drawing, which forms a part of the following specification.

The single figure as indicated in the drawing is a perspective view of my new design. I claim:

The ornamental design for a housing for a liquid-container vending machine, substantially as illustrated.

In testimony whereof I hereunto affix my signature.

JULIUS A. SAND, JR.
